UNITED STATES PATENT OFFICE.

WILLIAM C. FARNUM, OF WINCHESTER, MASSACHUSETTS, ASSIGNOR TO WILLIAM M. WHITNEY, OF WINCHESTER, MASSACHUSETTS.

WOOD-PLANING MACHINE.

1,275,163.

Specification of Letters Patent.

Patented Aug. 6, 1918.

Application filed May 12, 1917. Serial No. 168,144.

To all whom it may concern:

Be it known that I, WILLIAM C. FARNUM, a citizen of the United States, residing at Winchendon, county of Worcester, and State 5 of Massachusetts, have invented an Improvement in Wood-Planing Machines, of which the following description, in connection with the accompanying drawings, is a specification, like characters on the drawings 10 representing like parts.

The invention to be hereinafter described relates to motor supporting, balancing and connecting devices, and more particularly to means for directly connecting motors to 15 wood planers.

As well understood by those skilled in the art, there are two general types of wood planers in common use at the present time, namely, the single surface planer and the 20 double surface planer. The single surface planer finishes one surface of a board or piece of timber, as its name implies, whereas, the double surface planer finishes both surfaces of the work. A single surface planer requires 25 only one cutter cylinder to act upon the single surface to be planed, while the double surface planer has two cutter cylinders, one for acting upon one surface of the work, and the other for acting upon the other surface 30 of the work. Inasmuch as the work or boards may differ in thickness, it is necessary that the cutter cylinder be adjustable to accommodate such varying thicknesses of the work; and it is also desirable that the 35 cutter cylinder be adjustable for varying the depth of cut.

Where the cutter cylinder is driven by a motor, such, for instance, as an electric motor, it is desirable that the driving member 40 of the motor shall maintain substantial axial alinement with the cutter cylinder which it drives.

An important feature of the present invention, therefore, consists in providing a 45 motor support which may be independent of the main supporting frame of the planer, and interposing means between the cutter cylinder or its adjusting devices and the motor, so that upon adjustment of the cutter cylinder in a direction at substantially 50 right angles to its longitudinal axis, or for

varying thicknesses or work or depth of cut, the motor may be automatically adjusted or moved in the plane of cutter adjustment relative to its support.

55

Various means may be employed for carrying this feature of the invention into practical effect, and in the present instance, the motor is counter-balanced by means such as a weight or spring, and guided on a support 60 which may be moved into proper position relative to the planer, so that upon adjustment of the cutter cylinder, the motor may be readily moved automatically with the cutter cylinder to maintain the driving 65 member of the motor in substantial axial alinement with the cutter cylinder. It is obvious that the same means may be used to attach a motor to various other types of machine, in which the driven shaft is movable 70 vertically.

It is desirable at times to move the motor from its driving position in order to manipulate the cutter cylinder, and to this end another important feature of the invention 75 consists in so supporting the motor in operative relation to the cutter cylinder, that the motor may be readily moved from driving position when desired.

In carrying the present invention into 80 practical effect, the motor may be mounted on a support independent of the main frame, or such support may be adjustably connected to the main frame, the construction being such that the motor may be adapted for 85 driving the cutter cylinder of planers already in use not originally designed to be driven by a directly connected motor.

The above and various other features of 90 the invention will be best made clear from the following description and accompanying drawings showing one good, practical form of the invention as applied to a double surface planer, it being understood, of course, that changes and variations may be made in 95 the details of construction, without departing from the scope of the present invention, which is definitely set forth by the claims.

In the drawings:

Figure 1 is a perspective view of a double 100 surface planer having the present invention associated therewith.

Fig. 2 is a side elevation partly in section, showing a modified form of support and counter-balance for the motor.

Fig. 3 is a section on the line 3—3 of Fig. 2, showing the motor support of Fig. 2 and the connection between the motor driving member and the cutter cylinder.

Fig. 4 is a side elevation of the machine shown in Fig. 1 on an enlarged scale and 10 some of the parts being broken away.

Fig. 5 shows one form of convenient connection that may be employed for operatively connecting the motor driving member and the cutter cylinder.

15 Fig. 6 is a side elevation with some of the parts broken away, showing another modification of the motor support means.

Fig. 7 is a plan view of the construction shown by Fig. 6, and illustrating in sectional detail the convenience of such connection between the motor driving member and the cutter cylinder.

Referring more directly to Fig. 1 which typifies one general form of planer, the 25 main supporting frame comprises the side frames 1 which are connected by suitable cross braces 2, said frame being of a character adapted to support the operating parts of the planer.

30 In exploitation of the present invention, it will be convenient to describe the motor and its association with the lower cutter cylinder as indicated in Figs. 1 and 4, and as embodied in a double surface planer, but 35 it will be understood that the invention is not limited in these respects.

The cutter cylinder 3 (Figs. 1 and 4) is mounted upon its supporting shaft or axis 4 which is sustained in suitable bearings 5, 40 one at either side of the machine. The bearings 5 may be of any suitable character, and in the present instance of the invention, they are shown as rising from a supporting member 6 which rests upon the top portion 45 of a wedge 7, the inclined lower surface of the wedge 7 bearing upon a vertically adjustable member 8, the inclined lower surface 9 of which rests upon the adjusting wedge 10.

50 Secured to and movable with the member 8 is the table 11 on which the work is placed and over which it travels during the surfacing operation. The wedges 7 and 10 may be properly adjusted by any suitable means, 55 one convenient form of which is shown in Fig. 4 as comprising a screw shaft 12 which may be conveniently turned by the gear 13 operated by any suitable means, as well understood by those skilled in the art. From 60 the construction described, it will be noted, that upon adjustment of the wedge 10 the entire frame 8 including the cutter cylinder and table 11 will be moved in a vertical direction toward and from the opposed work 65 engaging devices, which, in the present in-

stance of the invention, may comprise the rolls 14 and 15, thereby accommodating the relation of the cutter, cylinder, table, and the opposed work engaging members for variations in thickness of work. If desired, 70 the rolls 14 and 15 as well as the under rolls 16 and 17 may be appropriately driven to constitute feed rolls for the work. Should the wedge 7, however, be adjusted on the frame 8, it will serve to move the cutter cylinder relative to the table 11 to vary the 75 depth of cut.

Rising from the base portion 18 of the motor support is the post or stand 19 having guideways 20 for engagement with complementary guide members 21 connected to the motor 22, the construction being such that the motor 22 may move in the guideways 20 in the plane of cutter cylinder adjustment when the motor support 18 and 19 85 is placed in operative relation to the main frame of the surface planer. In Fig. 1 the base portion 18 of the motor support may be provided with some convenient form of means such as the bolts 23 for securing the 90 motor support in such position that the motor 22 when moved in the guideways 20 will be confined to the plane of cutter cylinder adjustment.

Rising from the post or stand 19 of the 95 motor support are the bracket members 24 carrying a roll 25 over which passes a flexible connection 26 between the motor 21 and the counter-balance 27. The counter-balance, in the form illustrated by the Fig. 1, 100 comprises a weight 27 and is of sufficient mass to substantially counter-balance the weight of the motor, the construction being such that should a slight force be applied to move the motor 22 in the guideways 20 105 of the motor support, the motor will readily respond to such slight actuating force. Obviously, instead of using the weight 27 as in Fig. 1 to counter-balance the motor 22, equivalent means might be employed, such, 110 for instance, as a spring, which is the well known equivalent of a weight for the purposes described.

In order that the motor 22 may actuate the cutter cylinder 3, a suitable clutch connection is employed. This, in the illustration shown by Figs. 1, 2, and 3, comprises an Oldham clutch, that is, there are two clutch members 28 and 29, each provided with a groove and having interposed between them the floating member 30, the construction being such that upon rotation of the motor the cutter cylinder will be suitably actuated. From the construction described it will be apparent that should the 125 cutter cylinder 3 be adjusted at right angles to its longitudinal axis, as for instance, to accommodate the machine to different thicknesses of work or for variations in depth of cut, the clutch connection described 130

between the cutter cylinder 4 and the motor will transmit sufficient force to move the counter-balanced motor in the plane of and in the direction of cutter cylinder adjustment.

The Oldham clutch connection between the cutter cylinder and driving member of the motor constitutes not only a convenient form of driving connection between the two, but serves also to cause the motor to be moved with the cutter cylinder as the latter is adjusted either for thickness of work or depth of cut. Instead, however, of providing a clutch between the driving member of the motor and the cutter cylinder which will cause movement of the motor with the cutter cylinder as the latter is adjusted, any convenient means may be employed between the cutter cylinder and motor which will effect movement of the motor with the cutter cylinder as the latter is adjusted. One form of such means is indicated in Fig. 5, wherein, the axis or shaft 4 of the cutter cylinder is provided with a clutch member 31 having toothed portions 32 adapted to engage complementary toothed portions 33 in a clutch member 34 secured to the driving member 35 of the motor. The clutch member 34 may be secured to the driving member 35 of the motor by any convenient means, and as herein illustrated, it is secured thereto by means of the set screw 36 and a spline or key 37. From the construction described, it will be apparent that the cutter cylinder will be rotated by the driving member of the motor which is in substantial axial alignment with the cutter cylinder, and in order that the motor may be automatically moved with and in the same direction as the cutter cylinder as the latter is adjusted in a direction at right angles to its longitudinal axis, the clutch member 34 may be provided with a socket portion 38 into which may project a pin connected to the cutter cylinder or other part movable therewith, substantially as indicated in Fig. 4, wherein, the end of the cutter cylinder shaft 4 extends into socket portion 38 of the clutch member 34, the construction being such that as the cutter cylinder is adjusted, the pin or shaft 4 of the cutter cylinder will transmit sufficient force through the clutch member 34 for moving the counter-balanced motor automatically in the plane of adjustment of the cutter cylinder.

Instead of the construction of motor support as indicated in Fig. 1, other forms of motor supports may be employed independent of the main frame of the machine, as for instance, in Fig. 2 the motor support may comprise a column 39 rising from a base 40 and formed with a hollowed portion 41 in which may be guided the counter-balancing weight 42. As illustrated in Fig. 2, the motor is mounted upon a sleeve 43

which may rise and fall on the column 39, and extending from the top portion of the column 39 is an arm 44 having the guide rolls 45 and 46 over which passes the flexible connection 47 extending between the motor 70 and the weight 42. The arm 44 is preferably swiveled in the top portion of the column 39 so that by disengaging the driving member of the motor from the cutter cylinder by disconnecting the clutch members the 75 motor in Fig. 2 and the arm 44 may be turned or swung laterally to enable any desired manipulation of the cutter cylinder.

It will be noted that in the modified form of motor support indicated in Fig. 2, the 80 counter-balanced weight 42 is guided within the column 39 and entirely inclosed thereby; whereas, in the form of support indicated by Fig. 1 the counter-balanced weight 27 is guided for movement between the guide- 85 ways 48 secured to the post or upright 19.

Where the motor is counter-balanced by means of a weight and flexible connection between the weight and the motor, it is desirable to secure the flexible connection to 90 the motor at a point substantially in vertical alignment with the center of gravity of the motor, in order that all binding effect or opposition to motor movement by the cutter cylinder may be obviated. 95

Figs. 6 and 7 indicate a still further modified form of the motor support, in which the base portion 50 has rising therefrom a post 51 which may be circular in cross section. Mounted for movement longitudinally of the post 51 is the motor carrying sleeve 52 from which projects the motor supporting arms 53. In the form of construction illustrated by Figs. 6 and 7, the motor 22 is preferably provided with the 100 socket portions 54 adapted to be engaged by the ends of the adjusting and sustaining pins 55 which may be held in supporting position relative to the motor by means of lock nuts 56, said pins 55 passing through 105 and being threaded to the supporting arms 53 substantially as indicated in Fig. 6.

The motor indicated in Figs. 6 and 7 is suitably counter-balanced. In the present instance, such counter-balance is effected 115 by means of the weight 57 which may be connected to the motor by the flexible connection 58 passing over suitable guide rolls 59 and 60 supported by the cross head 61. The cross head 61 may be supported upon 120 the post or column 51 by suitable ball-bearing connections as indicated in Fig. 6, whereby, upon swinging movement of the motor and its sleeve 52 on the post or column 51 to move the motor to one side of 125 its driving position relative to the cutter cylinder, the cross head 61 may similarly move in unison therewith. Of course, very many obvious substitutes may be employed 130 for the practice described with respect to the

construction shown by Figs. 6 and 7, but the above constitutes a good, practical form of this feature of the invention. Of course, instead of the sleeve 52 mounted for swinging movement on the post or column 51, the column 51 might be mounted to swing in its supporting base 50, but these are details which readily suggest themselves as mechanical equivalents to those skilled in the art.

- 10 Where the counter-balanced motor is mounted to swing to one side of its operative position relative to the cutter cylinder, it is necessary, of course, that the clutch connection between the driving member of the 15 motor and the axis or shaft of the cutter cylinder be detachable, and at the same time that there be some means between the cutter cylinder or its supporting bearing and the motor to cause the motor to be moved automatically with the cutter cylinder as the latter is adjusted.

In the present instance, as illustrated in the modification of Figs. 6 and 7, the cutter shaft 4 is provided with a disk 62 having a 25 cap piece 63 secured thereto by suitable means such as the bolt 64. The driving member of the motor is provided with a head piece 65, preferably of rounded form as illustrated in Fig. 7, and adapted to be 30 held in operative relation with the cutter cylinder shaft 4 by the cap 63 as illustrated in Fig. 8. The construction so far described will cause the motor to be moved in the plane of and with the cutter cylinder as it 35 is adjusted. To effect rotative movement of the cutter cylinder, the shaft 4 of the cutter cylinder is provided with a non-circular or squared portion 66 adapted to be received in a similarly formed socket in 40 the head 65 of the motor driving member.

From the construction described it will be apparent that the motor will be held by its support with its driving member in substantial axial alinement with the cutter cylinder shaft, and as the cutter cylinder is adjusted on the main supporting frame, the counter-balanced motor will be automatically adjusted in the same direction as and in the plane of the motor cylinder adjustment, and such movement of the motor 45 will be effected by the exercise of slight force, owing to the fact that the motor is counter-balanced. It will also be apparent that the motor support may be quite independent of the planer and be adapted to support a counter-balanced motor in operative relation to the cutter cylinder of the ordinary planers now in use. It will also be apparent from the construction described, 50 that when it is desired to manipulate the cutter cylinder or remove it by withdrawing it endwise from the main frame of the planer, the motor may be moved or swung to one side out of the way, and when the 55 cutter cylinder has been replaced or another

one substituted, the motor may be readily swung back into operative axial alinement with the cutter cylinder shaft.

While the invention has been described as associated with a wood planer, and while the claims refer to a cutter cylinder, it is to be understood that the motor and the motor supporting, balancing and connecting devices may be employed in any type of machine wherein the shaft to be driven by the motor is adjustable in a direction at right angles to its longitudinal axis, and the claims are intended to be sufficiently comprehensive to include such constructions.

Claims.

1. The combination with a normally fixed tool and its support, of an independent driving unit for association with said tool comprising a motor, means directly to connect said motor with said tool to rotate the latter, and supporting means for said motor including means to counterbalance the motor and enable the same to adjust itself to the position required by the tool.

2. The combination with a tool and its support, of a motor having its driving member substantially in axial alinement with the axis of said tool, supporting means for said motor including means to counterbalance said motor, and means to connect said member with said tool that the motor may adjust and maintain itself substantially in alinement with the axis of said tool.

3. The combination with a tool, of a support therefor, means to adjust said tool relatively to said support to different fixed positions, a motor having a driving member, supporting means for said motor including means to counterbalance said motor, and means to connect said driving member to said tool, that the motor may automatically share the adjustment of said tool.

4. The combination with a rotary tool and its support, of means to adjust said tool relatively to said support, a motor having a driving member, means detachably to connect said member with said tool substantially in axial alinement therewith, and means to support and counterbalance said motor.

5. The combination with a rotary tool and its support, of a motor having its driving member substantially in axial alinement with the axis of said tool, means detachably to connect said driving member with said tool, and supporting means for said motor including counterbalance means therefor and means to allow said driving member to swing out of axial alinement with the axis of said tool.

6. The combination with a rotary tool, of a normally fixed support therefor; a driving unit for association with said tool comprising a motor having a driving shaft, means to connect said shaft with said tool to rotate the same, means to counterbalance

said motor, a support for said motor and for said counterbalance means, and means to guide said motor as it adjusts itself to the position required by the tool.

7. The combination with a rotary shaft, of a support for said shaft, a motor having a member for driving said shaft, means to counterbalance said motor, means to support said motor and counterbalance means, and connecting means between said shaft and member for maintaining said motor driving member substantially in alinement with the axis of said shaft.

8. The combination with a cutter cylinder, of a support therefor, means to adjust said cylinder in a direction at substantially right angles to its longitudinal axis, a motor having a driving member, means to counterbalance said motor, means to support said motor and counterbalance means and means flexibly to connect said driving member with said cutter, that said member may be maintained substantially in axial alinement with the axis of said cutter cylinder.

9. The combination with a frame, of a table and a cutter cylinder thereon, work engaging means opposed thereto, means for effecting simultaneous adjustment of the

table and cutter cylinder toward and from the work engaging means for variations in thickness of work, means for effecting adjustment of the cutter relatively to the table to vary the depth of cut, a motor having a driving member, means to counterbalance said motor, a support for said motor and counterbalance means, and means connecting said driving member with said cutter for automatically moving said motor on its support in the direction of the cutter adjustment.

10. The combination with a rotary tool, of a normally fixed support therefor; and a driving unit for association with said tool comprising a motor having a driving member, a standard, means to counterbalance said motor, means to connect said driving member with said tool for automatically adjusting the motor relatively to said standard to the position required by said tool, and means connecting said motor with said standard to guide said motor as it is adjusted relatively to said standard.

In testimony whereof, I have signed my name to this specification.

WILLIAM C. FARNUM.
